UNITED STATES PATENT OFFICE

155,692

DESIGN FOR A CABINET FOR LUBRICATING EQUIPMENT

Alexander P. Fox, University City, and August D. Reisert, St. Louis, Mo., assignors to Lincoln Engineering Company, St. Louis, Mo., a corporation of Missouri

Application March 6, 1948, Serial No. 144,934

Term of patent 3½ years

(Cl. D52—2)

To all whom it may concern:

Be it known that we, Alexander P. Fox and August D. Reisert, citizens of the United States and residents of University City, St. Louis County, Missouri, and St. Louis, Missouri, respectively, have invented a new, original, and ornamental Design for a Cabinet for Lubricating Equipment, of which the following is a specification, reference being had to the accompanying drawing forming part thereof, in which

Fig. 1 is a front perspective view of a cabinet for lubricating equipment showing our new design;

Fig. 2 is a plan view;

Fig. 3 is a rear elevation; and

Fig. 4 is an end elevation of the right-hand end of the cabinet as viewed in Figs. 1 and 2.

The dominant features of our new design reside in the portion shown in full lines.

We claim:

The ornamental design for a cabinet for lubricating equipment, substantially as shown and described.

ALEXANDER P. FOX.
AUGUST D. REISERT.
